UNITED STATES PATENT OFFICE

2,287,980

DOOR LOCKING MECHANISM

Alexander C. Findlay, Flint, Mich.

Application October 23, 1939, Serial No. 300,720

14 Claims. (Cl. 70—264)

My invention relates to new and improved locking and latching mechanism for doors, and more particularly to the locking and latching mechanism of a plurality of doors, say specifically those of an automobile, whereby any number or all of the doors may be locked or unlocked from one or more central lock-controlling stations, which may be placed either exteriorly or interiorly, or both, of the body.

Attempts have heretofore been made to produce a coincidental locking mechanism or system by which all of the doors of an automobile may be locked from a single station. It is desirable, although not essential, in a structure of this type:

- (1) That the system be simple and admit of easy manufacture and application for use;
- (2) That, after locking, the door handles will be disassociated from their respective latch bolts so that movement of the door handles will be ineffective to cause any corresponding movement of the latch bolt;
- (3) That the motion-transmitting mechanism from the interior or exterior central control to the other doors in the system be amply protected so that the insertion of sharp instruments or the like will be ineffective to force an opening of the door; and,
- (4) That the action of locking from the exterior should be so related to the action of locking from the interior as to be independent thereof, thus rendering it impossible, when the vehicle has been locked from the outside, to effect an entrance by breaking a window or the like to open the doors from the interior.

These features and others have been disclosed in United States Letters Patent No. 2,180,819, granted to me November 21, 1939. However, it has been found that another and important requirement must be taken into consideration in coincidental locking systems of this character if they are to fully serve their purpose. Provisions should be made so that when any one of the doors in the system is open or improperly latched, it will be impossible to lock the remaining door or doors, either from the interior or from the exterior.

It is, therefore, a broad object of my invention to provide a multiple door locking construction wherein none of the doors may be locked while one remains open or is improperly latched.

Another object of my invention is to provide a simple and inexpensive locking system, which, due to its construction and arrangement of

parts, will readily admit of easy manufacture and installation and embody substantially all the essential requisites of a structure of this type.

A further object of my invention is the provision of a door locking and latching system which may be readily capable of meeting the requirements of all types of vehicles.

Other objects and advantages of the invention will be apparent to those skilled in the art from the following description when taken in connection with the accompanying drawings.

In the drawings:

Fig. 1 illustrates an embodiment of the invention as applied to an automobile of the sedan type having its doors opening forwardly of the body;

Fig. 2 is a diagrammatic illustration of the locking mechanism employed in the type of sedan shown in Fig. 1;

Fig. 3 illustrates an embodiment of the invention as applied to an automobile of the sedan type having its front and rear doors opening in opposed relation;

Fig. 4 illustrates diagrammatically the locking mechanism employed in the type of sedan shown in Fig. 3;

Fig. 5 is an enlarged perspective view of that part of the locking mechanism embodied in the door employing key means for operating the locking mechanism of all the doors, this structure being known as the master lock or exterior central control;

Fig. 6 is a similar view of the same structure but looking at it from a different angle;

Fig. 7 is a perspective view similar to Fig. 6, but illustrating the locking mechanism embodied in the doors omitting the key means, being known as the controlled mechanism;

Fig. 8 is an elevational view of the structure shown in Figs. 5 and 6, effecting an exterior locking operation with the parts in position to effect normal latching of the door;

Fig. 9 is a similar view, but showing the parts in a normal unlatched position;

Fig. 10 is also a similar view, but showing the position of the parts when the first two steps in the locking operation have been performed, that is, the key has been turned in the lock and the door handle has been moved to effect actuation of the locking mechanism;

Fig. 11 is a similar view illustrating the parts in the same position as shown in Fig. 10 but with the key withdrawn;

Fig. 12 discloses the positions of the parts when the door handle has been moved but the latch

bolt and its cooperating elements are no longer in position to be affected by the aforesaid motion, that is to say, the door has been locked, this view illustrating the manner of freeing the handles from the bolts to prevent forcing of the lock by pressure on the handles when in their locking position;

Fig. 13 is an elevational view of the structure shown in Fig. 7 omitting the key means and herein called the controlled lock structure, the parts being shown in normally latched position;

Fig. 14 is a similar view, but illustrating the parts in position of the first stage of the locking operation;

Fig. 15 is also a similar view, but showing the parts in locked position;

Fig. 16 is an enlarged section substantially along line 16—16 of Fig. 8;

Fig. 17 is an enlarged section along line 17—17 of Fig. 8;

Fig. 18 is a fragmentary section of the lock cylinder substantially as illustrated in Fig. 17, but with the parts in a position to effect locking;

Fig. 19 is a fragmentary section taken on line 19—19 of Fig. 8;

Fig. 20 is a fragmentary edge view of an automobile door to which my invention has been applied;

Fig. 21 illustrates somewhat diagrammatically the action of the mechanism employed in my construction for preventing the locking of any door while the master door remains open or improperly latched, and is here shown with the door closed;

Fig. 22 illustrates the changed position of the mechanism shown in Fig. 21 when the door is open or improperly latched;

Fig. 23 discloses the mechanism by which the locking action of the interior locking means may be transmitted to the other doors in the system to effect a locking or unlocking operation, and further shows the device by which the locking of any doors will be prevented when any of the several doors of the system are open;

Fig. 24 illustrates a position of the above described mechanism when all the doors are closed;

Fig. 25 is a sectional view substantially on the line 25—25 of Fig. 23;

Fig. 26 shows a mechanism for transmitting the motion of either an interior or exterior locking operation to other doors in the system and would preferably be used with a construction such as is shown in Figs. 3 and 4;

Fig. 27 illustrates a modification employing a single disabling pawl for the key-controlled or master locking mechanism; and

Fig. 28 illustrates a modification employing a single disabling pawl for the controlled locking mechanisms.

The mechanism shown herein and embodying the invention is capable of a rather broad application and may be embodied in automobiles having their doors opening in different directions, Figs. 1 and 3 illustrating bodies of the sedan type employing front and rear doors, it being evident from these two illustrations that from the practical standpoint there is no limitation with respect to the arrangement of the parts comprising the invention, and their embodiment in automobile bodies of the four-door or two-door type, or any other arrangement of doors, may be varied as desired.

It will be also understood at the outset that although the invention is illustrated in the

drawings as being particularly adapted to locking of doors of an automobile, the construction shown may be employed in locking any number of doors thereof, or trunk doors or other parts of the vehicle, or all or any number of doors of structures other than automobile vehicles.

Referring now to the drawings in detail, and more particularly, to Figs. 1 and 2, there is illustrated a lock and latch mechanism for each door, the same being designated as 2, 3, 4 and 5, each lock being provided with an exterior cooperating handle 6 and an interior cooperating handle 7. It may be noted further that each lock is provided with a housing 8 having a cover 8' (see Fig. 16) and a latch bolt 12, which acts normally to keep the door latched in closed position. Each bolt 12 acts to keep the doors either locked or latched in accordance with the disposition of the other cooperating elements. These latter elements, apart from those within the housing 8 of each lock structure, comprise pivotally mounted discs 14 for the interior central control mechanism and discs 15 for the exterior central control mechanism. Motion is transmitted either to or from these discs, in a manner to be fully described later, by means of link pins to be hereinafter described and by means of flexible connections 16 and 17 of any suitable type adapted to be arranged within the body of the vehicle in any suitable way to readily transmit motion.

The construction of the locking system, shown in Figs. 3 and 4, is substantially similar to that just described, the principal exceptions being that the lock structures 2 and 3, and the lock structures 4 and 5 are arranged oppositely. The means for transmitting motion from the exterior central control mechanism of structure 2 to the other lock structures in this case comprises pivotally mounted discs 15a and 15b, each set of discs having intermeshing teeth 18 and 19.

Referring to Fig. 4, the interior locking operation may be effected by means of an interior central control specifically illustrated herein as a small toggle lever 20, properly positioned within the vehicle, preferably within convenient reach of the driver, and secured to motion transmitting wire 17. Thus, motion applied to the lever 20 will be transmitted through the wire 17 to intermeshing toothed discs 14a and 14b and from thence will be transmitted to the lock structures 2, 3, 4 and 5.

In the same manner, the interior locking operation in the system shown in Figs. 1 and 2 may be effected by means of a similar toggle lever 20, or the like, properly and conveniently positioned in the vehicle and carried by or otherwise connected to wire 17. The showings in Figs. 2 and 4 are solely diagrammatic in this regard.

It will now be clear that my invention consists of a coincidental locking system providing interior and exterior locking operations. The exterior locking operation is effected through a plurality of parts comprising a central control, such as a key-operated device and motion transmitting mechanism for operating the several lock structures in the system. The interior locking operation is effected through somewhat similar parts but has an internally manually operable element as a central control which has been described above as element 20. These parts are so arranged and so operated as to comprise a unitary locking system. With the vehicle locked by the interior central control, it is impossible

to gain access to the interior of the vehicle by a key fitting the exterior central control, and before access may be gained to the interior, it is necessary for the interior central control to be moved to unlocked position. With the vehicle locked by the exterior central control, it is impossible to release the locking mechanism to open the doors by breaking the windows and actuating the interior central control or the interior door handles.

It is believed that the foregoing will make clear the general purposes and functions of the system as a whole, and consequently, the specific details of construction as embodied in this disclosure will now be described.

The construction of the key-controlled or master locking mechanism, known as the central station or exterior central control, is shown generally in Figs. 5 and 6, while the various positions of its parts during operation are shown in Figs. 8 to 12, inclusive. As shown, housing 8 or its equivalent is adapted to carry cylinder 22. Exterior handle 6 is mounted upon a shaft 23 extending into housing 8. Shaft 23 has fixedly secured thereto a link 24 which transmits the movement of handle 6 to the interior of the lock. Springs 25 and 26 are arranged so as to maintain the link 24 in what may be regarded as a normal position by means of the pin 27 and the pin 28, the latter being secured to housing 8 and being designed to prevent either of the springs 25 or 26 from acting while the other is under tension.

Secured to link 24 by means of a pivot pin 29 is a cross link 30 which cooperates at its other end with a draw link 32 by means of a stud pin 33 riding in an elongated slot 31. Movement of link 24 by handle 6 in a clockwise direction, as shown in Figs. 5 and 6, will cause a counter-clockwise movement of link 32 by means of link 30. Integral with link 32 and bent inwardly therefrom is a hooked portion 34 arranged to engage a hook 35 on a latch bolt link 36. This link 35 is secured to latch bolt 12 by a pin 37 and has a pressure exerted downwardly thereon by means of a spring 38 carried by pin 37 and attached at 38' to link 35. Counterclockwise movement of link 32 about its pivot 32a will cause a withdrawal of the latch bolt 12 from its keeper.

A link 39 having a slot 40 is connected by means of a pin 40a to link 32. Link 39 is pivotally connected to interior handle 7 by means of a pin 42, which handle 7 may be pivoted at 41, so that when it is turned clockwise about its pivot 41, as viewed in Figs. 5 and 6, link 32 will be actuated in a counter-clockwise direction about its pivot 32a. When exterior handle 6 operates link 32 in this direction through link 30, pin 40a will slide in the slot 40 and prevent operation of handle 7. When handle 7 operates link 32, pin 33 will slide in slot 31 and prevent operation of handle 6. Hence, movement of either handle will not effect movement of the other handle.

Referring again to link 32, it may be noted that the same is secured at its lower extremity by a pivot pin 32a about which it moves. Secured to the pin 32a is a coil spring 32b fixed at one end to the pin 32c and at the other end to link 32 in such a manner as to cause the said link to return to normal position after it has been actuated by handles 6 and 7. However, spring 32a is not sufficiently strong to overcome spring 25 through movement of link 24.

Each lock mechanism is preferably provided

with two sets of pins, the upper set being designated 50 and 51, and the lower set being designated 55 and 56. The inner ends of these pins are pivoted to a pair of discs 44 and 45, pivotally carried by a pintle 43. Pintle 43 is preferably carried in housing 8 and its cover plate 8'. Upper pins 50 and 51 are connected to discs 44 and 45 at the points designated 52. Lower pins 55 and 56 are connected to discs 44 and 45 in a similar manner at 52'. Discs 44 and 45 are provided with projecting elements 47 and 48 which are adapted to strike against the underside of and lift a pin 49 when either of discs 44 or 45 is rotated in clockwise direction. This lug 49 extends at right angles from the upper edge of link 36, as clearly shown in Fig. 6. Link 36 is then lifted when either disc 44 or 45 is rotated in a clockwise direction in order to disconnect handles 6 and 7 from latch bolt 12 by breaking the connection between hooked portions 34 and 35.

The pivotal connections 52 and 52' are so arranged with respect to the mounting of discs 44 and 45 that movement of disc 44 will reciprocate pins 50 and 55, to-wit, clockwise rotation of disc 44 will extend pin 50 beyond housing 8 and will withdraw pin 55 into housing 8 whereas counterclockwise rotation will withdraw pin 50 and will extend pin 55. When disc 44 is rotated to its position shown in Fig. 8, wherein the parts are shown in position of normal latching, the ends of pins 50 and 55 will be flush with the exterior of the side of housing 8. Likewise, clockwise rotation of disc 45 will extend pin 51 and withdraw pin 56, whereas counterclockwise rotation will withdraw pin 51 and extend pin 56. Conversely, a movement of pin 50 or 51 to the left will rotate disc 44 or 45 counterclockwise and will produce a movement of pin 55 or 56 to the right. I preferably provide bearings 57 and 58 for supporting the outer ends of lower pins 55 and 56 when they are moved inwardly in the course of their operation, as will be hereinafter described, and to guide them into the openings provided for them in housing 8 as they are subsequently projected outwardly.

It will now be clear that movement of the push pin 51 to the right will cause it to extend beyond the slot 54 and will cause the push link 56 to be withdrawn into its bearing 58 and will further cause a rotary motion to be applied to the disc 45. In this manner, link 36 through projections 48 and 49 will effect disengagement of the hooks 34 and 35 by lifting hook 35 out of engagement with hook 34. When these members are thus disengaged, movement of draw link 32 will no longer be effective to cause a corresponding movement of latch bolt 12. Moreover, at this time, handle 6 may be moved until the link 24 strikes a stop pin 59 and the latch bolt will remain unmoved.

To effect movement of push pin 51, lock cylinder 22 has an extension in the form of a pin 60. See Figs. 5, 8-12, 17 and 18. In Fig. 17, the key 62 is shown inserted in the lock, while in Fig. 18 it is shown rotated approximately 180°, causing pin 60 to be raised and to lift therewith a link 64. The position of pin 60 and link 64 in Fig. 17 corresponds to the position of these elements in Fig. 5. Link 64 is provided with a guide slot 65. A pin 66 secured to the wall of housing 8 is adapted to ride in slot 65. Link 64 carries a pivot pin 67 having an elongated bar 68 attached thereto, the upper end of which is adapted to extend between and to be engaged by lugs 69 and 70 of push pin 51. The lower ex-

tremity of bar 68 is adapted to strike against either side of a fixed pin 71. Lifting link 64 will cause a corresponding lifting movement of bar 68, which will be raised sufficiently to be engaged by a lug 72 on the link 30, and which will at the same time clear the pin 71. Thus, when the key has been turned in the lock and the link 64 and the bar 68 have been raised, movement of exterior handle 6 in non-bolt retracting position will move links 24 and 30 and cause bar 68 to press against lug 70 whereby pin 51 will move outwardly through opening 54. Fig. 10 illustrates this action clearly. While these elements are maintained in the position shown in Fig. 10, key 62 is returned to its position, as shown in Fig. 11, thus lowering the bar 68 to clear lug 72 on bar 30. The handle may then be released from whence it will return to normal position and carry with it its cooperating elements, which will also, of course, return to their respective normal position, but push pin 51 will remain extended, as shown in Fig. 12, until the aforescribed procedure has been reversed. However, it will not be necessary in every instance to hold handle 6 until key 62 is returned to normal position because friction in flexible cables 16 may be relied upon to prevent undesirable restoration to unlocked position before key 62 is thus returned.

An angularly disposed lug 36a is secured preferably to the inner wall of housing 8, as clearly shown in Figs. 5 and 6, and is provided with a guide portion 36b arranged to overlie hook portion 35 of link 36. When link 36 is raised to effect disengagement between hooks 34 and 35, the lateral wall of lug 36a will lie in close proximity to the outer edge of hook 35, whereby rearward movement of link 36, while in raised position, is prevented. It will, therefore, be impossible to withdraw latch bolt 12 from its locked position by forcing this latch bolt through picking, or otherwise.

In order to restrict the range of movement of pins 50, 51, 55 and 56, discs 44 and 45 are each provided with lugs 44a and 45a arranged to lie in the path of a fixed pin 43a secured to, say, housing 8 so that movement of discs 44 and 45 in either direction will cause one of these lugs to strike pin 43a and thus limit the movement of the discs. Pins 50, 51, 55 and 56 are, consequently, prevented from being abnormally projected from or withdrawn into housing 8 and are accordingly held within a normal operating range.

Figs. 8 to 12, inclusive, illustrate the master lock mechanism or exterior central control and its parts in their various positions of operation. Fig. 8 shows the various parts in an unlocked but latched position. In this position, hook members 34 and 35 are engaged and discs 44 and 45 are in normal unlocked position. The outer ends of push pins 50, 51, 55 and 56 lie substantially within their openings 53, 54, 57 and 58 in side wall 73 of housing 8.

Fig. 9 shows the position of the parts when the exterior door handle 6 has been moved to effect a normal unlatching operation. In this view, it will be clear that the movement of links 24, 30 and 32 will effect withdrawal of bolt 12 to permit the door to be opened. Unlatching of bolt 12 by interior handle 1 will be effected in substantially the same manner, link 39 instead of link 30. When link 32 is moved by link 39, pin 33 is free to ride in slot 31 in link 30 without moving the latter.

Essentially, unlatching movement is effected by swinging link 32 in a counterclockwise direction about its pivot 32a so that its hook portion 34 engaging hook 35 will move link 36 to the left, as shown in Fig. 9, to withdraw latch bolt 12 from its keeper. The simplicity of the parts provided to carry out the present invention will readily be appreciated in connection with this operation, because either exterior handle 6 or interior handle 1 has control of the latch bolt to withdraw it from latching position as long as hooks 34 and 35 engage each other. However, separation of these hooks 34 and 35, caused by the lifting of link 36 upwardly about its pivot 37, against the action of spring 38, breaks operating relation between either of these handles and the latch bolt.

Fig. 10 illustrates the position of the parts of the master lock mechanism after key 62 has been inserted and turned 180°, and further, after exterior handle 6 has been moved to set the parts in locked position. Releasing exterior handle 6 to allow its return to normal latching position of bolt 12 allows link 24 to assume the position shown in Figs. 5, 6 and 8, as the result of spring 26 being relieved of the tension it is placed under by pin 27 when handle 6 is moved to unlatching position. Spring 26 tends to keep link 24 in its normal latching position, as shown for example in Fig. 8, until pressure is exerted upon exterior handle 6 to cause pin 27 to bear against spring 25 and place it under tension. Link 24 is then moved to the position shown in Fig. 10. This movement is limited by one end of link 30 preferably striking side wall 73 of housing 8. Consequently, the movement of the handle to effect the locking operation is predetermined to effect a predetermined movement of these parts to their locking position and prevent any forcing that would cause the parts to be ruptured. Insertion of key 62 in lock cylinder 22 and a 180° movement thereof effects a lifting movement of link 64 and bar 68. The upper end of bar 68 is then raised beyond lug 72 on link 30, the lower end being raised above fixed pin 71. Movement of exterior handle 6 in a counterclockwise direction to cause pin 27 to place spring 25 under tension, as just described, whereby link 24 is moved to the position shown in Fig. 10, causes lug 72 to bear against bar 68 and tilt the same in clockwise direction about its pivot 67 at the lower end of link 64. This tilting movement of bar 68 forces it against lug 70 on pin 51 to move this link to the right whereby to rotate disc 45 clockwise until its lug 44a strikes against fixed pin 43a. Projecting element 48 of disc 45 is swung upwardly against lug 49 to lift link 36 and break engagement between its hook 35 and hook portion 34 on link 32. If any one of the doors of the system is not closed, link 51 will be prevented from being moved to the right whereby to disable the locking operation that results therefrom. The means provided to prevent this locking operation under such conditions will be presently described.

Fig. 11 illustrates the parts in locked position after key 62 has been removed and exterior door handle 6 returned to normal position. To withdraw key 62, it is preferable to return it to its original position. Its pin 60 will swing downwardly to its lower position, as shown in Fig. 11, thus lowering link 64 and bar 68. Upper end of bar 68 is then withdrawn from its position between lug 72 and 72a on link 30. Fig. 12 illustrates these parts in a position of complete locking and the result of operating exterior handle 6

at this time. With hook portion 34 disengaged from hook 35, it is impossible to move link 36 and withdraw bolt 12 by movement of link 32, either by links 30 and 24 operable by exterior handle 6 or by link 39 operable by interior handle 7.

The controlled locking structure for the other doors in the system is shown in perspective in Fig. 7 and its parts in various operating positions in Figs. 13 to 15. Each structure includes discs 44 and 45 carried upon pintle 43 supported by housing 8. Upper push pins 50 and 51 are pivotally connected at 52 to discs 44 and 45, and lower push pins 55 and 56 are pivotally connected at 53 to discs 44 and 45. Push pins 50, 51, 55 and 56 operate substantially in the same manner as corresponding push pins in the master locking structure shown in Fig. 6. Each latch bolt 12 is likewise provided with link 36 having a hook 35 co-operating with a hook portion 34 on link 32. Link 32 is provided with pin 33 adapted to ride in slot 31 in link 30. Link 30 is connected at 29 to link 24 operated by exterior handle 6 in the same manner as heretofore described. Discs 44 and 45 are provided with projections 47 and 48, respectively, adapted to bear against right angular lug 49 secured or fixed to link 36. When either disc 44 or 45 is rotated in a clockwise direction by operation of the push pins, either projection 47 or 48 will lift lug 49 and link 36 to separate the engagement between hook 35 and hook portion 34 whereby both handles 6 and 7 are disconnected from latch bolt 12. Operation of exterior handle 6 moves link 30 to the left to cause tilting of link 32 about its pivot 32a. Tilting movement of link 32 will result in rearward movement of link 36 to withdraw latch bolt 12 from the keeper to permit the door to be opened. A similar operation is obtained through the actuation of interior handle 7. Its link 39 will tilt link 32 about its pivot point 32a and against the action of spring 32b to withdraw link 36 rearwardly, and consequently, unlatch the bolt 12. When either handle is released, spring 32b will tend to return link 32 to its normal position. Spring 26 will function to return lever 24 to its normal position when handle 6 is actuated. The simple construction of the controlled locking structure is practically the same as employed for master lock mechanism 2 having the key-operated means to effect a locking operation.

Fig. 13 illustrates the parts of the controlled locking structure in normal latching relation which is substantially the same as shown in Fig. 7. Fig. 14 illustrates the same locking structures with its parts in locking position. Fig. 15 illustrates the same structure with the parts in a locking position after the handle is released to illustrate the manner in which both handles may be disconnected from the latch bolt.

The key-operated means of the master lock mechanism effects the exterior locking operation of all the doors, and therefore, operates disc 45 and its push pins 51 and 56 of each locking structure. Disc 44 and its push pins 50 and 55 will operate to effect an interior locking operation upon actuation of manually operated member 20 or its equivalent. Consequently, disc 44 and its pins 50 and 55 are omitted from the master lock mechanism, as shown in Figs. 8 to 12, inclusive. In Figs. 13 to 15, inclusive, both discs 44 and 45 and all their pins are illustrated but only disc 44 and its pins 50 and 55 are illustrated in their different positions of operation that will result from effecting an interior locking operation. It will suffice to say that disc 45 and its pins 51

and 56 will operate in substantially the same way and assume substantially the same positions when an exterior locking operation is effected through the master lock mechanism and movement of its pins is transmitted to the control structures in the other doors of the system.

It is possible at times for one or more doors of an automobile to be open or improperly latched without the operator of the vehicle being aware of this condition at the time of effecting either an exterior or an interior locking operation. If one or more doors should remain open or partially latched, the benefits to be derived from a locking system of the type herein described would be largely nullified. Consequently, provisions have been made in the structure herein disclosed to disable the operation of the movable parts with one or more doors open or improperly latched so that it will be impossible for either the exterior central control or the interior central control to operate and effect a locking operation. Failure of the key-operated means 22 or the manual element 20 to operate will immediately indicate to the operator that all the doors are not fully closed. The operator will thereby be required to close all doors before operating either central control and will not find at a later time that one of the doors had not been locked and access to the interior of the vehicle was possible because all the doors appeared closed but one had been deceptively held partially closed by the safety latch only.

This disabling mechanism comprises essentially a blocking device in the form of spring-pressed pivotally mounted pawls or equivalent members adapted to be operated by the movement of the door to closed position. These pawls may be carried either by the doors or by the frames adjacent the doors. The drawings illustrate the pawls in the front right door, that usually carries the key-operated lock, and in the adjacent frames for the other doors, but it is apparent that all the doors may carry these pawls and that, if desired, these pawls may be provided in all the frames and not in any of the doors. Referring particularly to Figs. 5, 6, and 8 to 12, inclusive, the exterior and interior locking operations will be affected by the position of the door carrying the master lock mechanism 2 through a set of pawls 85, both carried upon a pin 86. Pin 86 may be disposed between and carried by opposite walls of housing 8. Pawls 85 are disposed between push pins 50 and 51, and 55 and 56, adjacent the side wall 73 of housing 8 whereby their forward fingers 87 are adapted to extend through openings 88 in side wall 73 and their rear fingers 89 are adapted to move in the path of lugs 90 extending at right angles and carried by push pins 50 and 51. When rear fingers 89 of pawls 85 are in the path of lugs 90 of push pins 50 and 51, the latter are blocked against movement so as to prevent both the exterior and interior locking operations. Coil springs 91 are disposed about pin 86 and have one end bearing against the lower portion of forward fingers 85 and the other end bearing against wall 73. Springs 91 serve to tilt pawls 85 forwardly in order to project their forward fingers 87 through slots 88, thus bringing the rear fingers 89 upwardly and against lugs 90 to block movement of push pins 50 and 51. It will be apparent that whenever the door carrying this lock structure is in open position, springs 91 will tilt pawls 85 to the position just described whereby to disable both the exterior and the interior

locking operations. Fig. 5 illustrates disabling pawls 85 in their position when the door is in closed position. Fig. 6 illustrates disabling pawls 85 in their disabling position when the door is in open position. The effective manner by which these disabling pawls 85 function to prevent operation of the key-controlled means and the manual lever 20 to effect exterior and interior locking operations will be obvious from Figs. 5 and 6.

Whenever the door is moved to closed position, disabling pawls 85 are readily cammed into the position shown in Fig. 5 by means of a cam surface 92 disposed upon the surface of the keeper 93. See Figs. 8 to 12, 21 and 22.

Each controlled lock mechanism may be provided with cooperating disabling pawls 95 shown in detail in Figs. 23 and 24. In Figs. 13, 14 and 15, these disabling pawls 95 are shown in co-operating relation with a door. In either system shown in Figs. 2 and 4, the discs 14 and 15 or the toothed discs 14a and 15a for the controlled lock mechanisms will be cut away at 96 to provide shoulders 97. Disabling pawls 95 may be pivotally mounted in proximity to these discs so that their rear fingers 98 will engage shoulders 97 to block rotation of the discs when the forward fingers 99 project through openings 100 in the adjacent wall of the door frame. Pawls 95 may be mounted at 101 and have springs 102 tending to tilt the forward fingers 99 forwardly through openings 100. This action will bring rear fingers 98 into blocking relation with shoulders 97. Consequently, it will be impossible to operate the exterior or the interior central control until each door has been closed. The doors carrying the controlled lock mechanisms are designated for the purposes of convenience as 112 in Fig. 24. Doors 112 are provided with cam surfaces 103 adapted to engage and cam forward fingers 99 inwardly through openings 100 when these doors are swung to fully closed position. It will be understood that cam surfaces 103 will be so arranged on the side face or closing edge of doors 112 that they will not effect the proper camming action of disabling fingers 95 to release the blocking relation with either of discs 14 or 14a until each door has been completely closed and latch bolt 12 dropped into latching relation, permitting normal operation of the lock structure. The position of disabling fingers 95, when this blocking relation with these discs is broken, is shown in Fig. 24.

From the foregoing explanation it will be apparent that the disabling means disclosed herein, both for the exterior central control and the interior central control, is merely illustrative of an efficient form of structure that may be employed to accomplish the desired result, and that being illustrative only; this disabling mechanism may be embodied in various ways in a locking structure of the types disclosed without departing from the scope of the invention.

As previously stated, the means for transmitting the movement of the exterior and interior central controls or locking devices 22 and 20, respectively, and the other doors to disable the normal operating relation between either handles and their bolts whereby to prevent withdrawal of said bolts and the opening of these other doors, has been shown in Figs. 1 to 4, inclusive, and Fig. 26. Describing first this means as employed on a sedan type of automobile body having the doors hinged to open in opposite relation, as shown in Figs. 3, 4 and 26, wherein the front

and rear doors on each side are latched in keepers on an intermediate jamb or stile post, toothed discs 14a, 14b, 15a and 15b are arranged in intermeshing opposed pairs respectively and pivoted

5 within a stile post 105. Intermeshing discs 14a and 14b are each provided with a pair of upper and lower pins 106 and 107. The two intermeshing discs 15a and 15b of each pair are each provided with a pair of upper and lower pins 108 and 109. Pins 106 and 108 are preferably shorter than pins 107 and 109. These upper pins 106 and 108 are adapted to align with upper pins 50 and 51 in each locking mechanism while the lower pins 107 and 109 are adapted to align with

15 lower pins 55 and 56.

As previously stated, lower pins 55 and 56 of each locking mechanism are shorter than upper pins 50 and 51, and are, therefore, preferably guided in bearing blocks 57 and 58, the purpose 20 of which is to keep these lower pins 55 and 56 in alignment with pins 107 and 109 when the former are withdrawn into housing 8. In view of the length of upper pins 50 and 51, it is preferable to provide a headed tip 110 upon each pin 106 and 25 108 so that any play of these longer pins 50 and 51 will not throw them out of alignment with these pins 106 and 108. If desired, the side walls of intermediate stile post 105 may be provided with cylindrical members 111 to provide adequate 30 bearing surfaces for heads 110. A toothed disc of one of the pairs, say toothed disc 14a, is adapted to have flexible connection 17 connected thereto, which flexible connection may be entrained across the body of the car to the corresponding toothed disc 14a on the opposite side of the car. Flexible connection 16 may connect with either toothed disc 15a or 15b at one side of the car body and extend across the car body to the opposite side in order to connect with either 35 toothed disc 15a or 15b on this opposite side so that the exterior locking operation effected by the key-controlled means, designated broadly as 22, may be transmitted to the lock structures 4 and 5 on the opposite side of the car. It will 40 be apparent that this locking operation is transmitted from lock structure 2 to lock structure 3 through discs 15a and 15b. In order to transmit this locking operation to lock structures 4 and 5, flexible connection 16 is suitably arranged to extend 45 from one side to the opposite side of the car body. It is to be understood that flexible connections 16 and 17, shown in either Figs. 2 or 4, may be arranged in any practical manner or be of any desirable material to accomplish 50 their function of transmitting the locking operations herein described.

More specifically describing the operation of the means for transmitting movement of either of the central controls or locking devices 22 and 20, it will be noted that in the event the key-operated means 22 is actuated to lock the right-hand front door of an automobile, the upper longer pin 51 will move outwardly to project 55 through its opening 54 in housing 8 of locking mechanism 2 to engage the upper outside shorter pin 108 carried by the outside toothed disc 14a. This action will move the outer pin 108 to the right, as shown in Fig. 4, to rotate outer toothed disc 15a clockwise about its pivotal mounting. 60 The outside intermeshing toothed disc 15b will likewise rotate, but counterclockwise, thereby causing the lower outside longer pin 109 to project inwardly in bearing 58 of locking mechanism 3 to move pins 56 inwardly whereby to rotate disc 45 and to lift link 36 through cross

lug 49 and to break engagement between hook portion 34 and hook 35. As previously explained, lifting link 36 to break engagement between hook 35 and hook portion 34 disables the operating connection between the handles and the bolt of each locking mechanism so that the movement thereafter of the handles will be ineffective to unlatch bolts 12 from their keepers. Clockwise movement of outer toothed disc 15a draws the flexible connection 16 downwardly or towards that side of the car to result in an upward movement of this flexible connection on the opposite side of the car whereby to rotate the outer disc 15a clockwise and the outer disc 15b counterclockwise on this opposite side of the car. This rotational movement of these two outer discs 15a and 15b on the opposite side of the car will cause their lower pins 199 to project into and to press against lower pins 56 of locking mechanisms 4 and 5, thereby rotating discs 45 and lifting links 36, through cross lugs 49 of these locking mechanisms 4 and 5, thus breaking engagement between hook portion 34 and hook 35 and rendering both of these locking mechanisms inoperative.

The same sequence of operation between corresponding parts will result if the interior finger latch or link 20 of the interior central control is operated to lock the doors from inside of the car. The inner discs 14a and 14b and the flexible connection 17 will operate and rotate discs 44 by means of lower push pins 55. The connections between links 36 and 32 are thereby broken in substantially the same manner as previously explained, and both exterior and interior handles will be disconnected from latch bolts 12.

When it is desirable to unlock the doors, either by the key-operated means 22 if it has been used to lock the cars, or by the interior latch or lever 20 if the latter has been used, a reverse movement of either of the flexible connections 16 and 17 will reestablish the operating connection between the handles and their bolts of both doors on the opposite sides of the car.

When the locking mechanisms 2, 3, 4 and 5 are embodied in the doors of an automobile of the sedan type having both front and back doors opening forwardly of the vehicle body, as shown in Figs. 1 and 2, a slightly different arrangement of discs and flexible connection will obtain. For instance, a single set of discs 14 and 15 will be disposed in a vehicle body along the adjoining edge of the right-hand front door carrying locking mechanism 2 having the key-operated means 22. The rear door on this side of the vehicle, which carries the locking mechanism 3, will also be provided with a set of discs 14 and 15. The same is true on the opposite side of the car provided in locking mechanisms 4 and 5 in the doors. The outside discs 15 of each set cooperating with locking mechanisms 2 and 3 will be connected by a flexible connection designated 16. The outside discs 15 cooperating with locking mechanisms 4 and 5 on the opposite side of the body are likewise connected by a flexible connection designated 16. Both flexible connections may then be connected by a cross connection in any suitable way to effect proper transmission of movement from one side of the car to the opposite side, as shown in Fig. 2. Similarly, discs 14 cooperating with locking mechanisms 2 and 3 are connected by flexible connection designated 17. Discs 14 cooperating with locking mechanisms 4 and 5 are connected by flexible connection designated 17. These flexible connections 17

may then be connected by a cross connection 17 adapted to serve the same purpose as described for cross connection 16. Each disc 14 is provided with a short upper pin 106 and a long lower pin 107. Each disc 15 is provided with a short upper pin 108 and a long lower pin 109. These pins 106, 107, 108 and 109 function in the same manner as the corresponding pins associated with toothed discs 14a, 14b, 15a and 15b, and 10 will operate in the same manner as described in connection with the embodiment illustrated in Fig. 4. It is, therefore, deemed unnecessary to detail the operation of these locking mechanisms, shown in Fig. 2, when either the key-operated means 22 or the manually operated lever 20 is actuated to effect either an exterior or an interior locking operation. The parts of each locking mechanism will operate in substantially the same manner as heretofore described.

20 Figs. 27 and 28 illustrate the use of a single disabling pawl 85 for the master locking mechanism 2 and a single disabling pawl 95 for the controlled locking mechanisms 2, 4 and 5 instead of two, as heretofore described, it being apparent that it is not essential that two be provided because a single pawl may function as efficiently. In Fig. 27, pawl 85' is carried upon pin 86' to cause its front end 87' by action of spring 91', to project through opening 88' in wall 73 when the door carrying the lock structure 2 is open. The rear end 89a is, in this instance, provided with a reverse bend, as shown, in order to provide a cross part 89' adapted to lie in the path of both lugs 90 on push pins 50 and 51. 30 Outward movement of push pins 50 and 51 to effect a locking operation from the interior or exterior will be thereby prevented. By providing cross part 89' at the rear end 89a, only one pawl 85' is required to disable the interior and exterior locking operations when the door is open.

35 Substantially the same arrangement obtains for the lock structures 3, 4 and 5. Pawl 95' may have its rear finger 98a provided with a reverse bend to form a cross part 98' adapted to cooperate with shoulder 97 of both discs 14 and 15 as shown in Fig. 2, or 14a-b and 15a-b as shown in Fig. 4. The operation of a single pawl 95' is substantially the same as two pawls, the only difference being that rear finger 98a cooperates through its cross part 98' with shoulders 97 of both discs. A single spring 102' on pin 101' will tend to force pawl 95' into blocking position when the door is opened. In either instance, the interior and exterior locking operations are effectively prevented when any one of the doors carrying the lock structures 3, 4 and 5 is open.

40 From the foregoing description, it will be apparent that the lock structures herein disclosed are simple in construction and effective to accomplish the purposes set forth. The exterior central control is capable of effecting a locking operation by key means exteriorly of the car, while the interior central control is capable of effecting a locking operation by any suitable means that may be readily operated by anyone inside the car, say for example, the driver. Neither control will operate to effect a locking operation if one or more of the doors are not in fully closed position. The mechanism shown and described herein to accomplish this purpose is merely illustrative of a mechanism that can be readily adopted. This mechanism is effective to disable the operation of either exterior or interior cen-

tral control if the holding means is not in proper position to keep the doors closed.

Without further elaboration, the foregoing will so fully explain the gist of my invention that others may, by applying current knowledge, readily adopt the same for use under varying conditions of service, without eliminating certain features, which may properly be said to constitute the essential items of novelty involved, which items are intended to be defined and secured to me by the following claims.

I claim:

1. A system for locking a plurality of doors from a single station comprising, in combination, a latch bolt associated with each door, a handle for each door, means normally operatively connecting each handle with its associated bolt, means for disabling said last means and for disconnecting each handle from its associated bolt, a single controller, motion transmitting connections between said controller and said disabling means and operable by said controller, and means for disabling said motion transmitting connections and for preventing disconnection of all said handles from their associated bolts when one of said doors is not in a position to be latched by said bolts.

2. A system for locking a plurality of doors from a single station comprising, in combination, a latch bolt associated with each door, a handle for each door, means normally operatively connecting each handle with its associated bolt, means for disabling said last means and for disconnecting each handle from its associated bolt, a single controller, motion transmitting connections between said controller and said disabling means and operable by said controller, a post at one edge of each door, and means for disabling said motion transmitting means including a part on each post whereby to prevent disconnection of all said handles from their associated bolts when one of said doors is not in a position to be latched by its bolt.

3. A system for locking a plurality of doors from exterior and interior stations comprising, in combination, a latch bolt associated with each door, a handle on each side of each door for withdrawing said bolts and opening said doors, locking means operable from exterior and interior stations for preventing said handles from withdrawing said bolts to open said doors, and means for disabling said locking means if one or more of the doors are in open position.

4. A system for locking a plurality of doors comprising, in combination, a latch bolt associated with each door, exterior and interior handles on each door, means for connecting said handles of each door with their associated latch bolt independently of each other, means for locking said exterior handles against actuation of said latch bolts, means for locking said interior handles against actuation of said latch bolts, and means preventing operation of either of said locking means if one or more doors are not in a position to be latched by said bolts.

5. A system for locking a plurality of doors comprising, in combination, a latch bolt associated with each door, exterior and interior handles on each door, each handle being adapted to withdraw its associated latch bolt and open the door independently of movement of the other handle on the door, locking means associated with said exterior handles for effecting a locking operation exterior of said doors whereby to prevent both said exterior handles and said interior handles

from withdrawing said latch bolts, locking means associated with said interior handles for effecting a locking operating interior of said doors whereby to prevent both said exterior handles and said interior handles from withdrawing said latch bolts, and means associated with all said doors for preventing the operation of both of said locking means if one or more of said doors are not in a position to be latched by said bolts.

10 6. A system for locking a plurality of doors comprising, in combination, a latch bolt associated with each door, exterior and interior handles on each door, each handle being adapted to withdraw its associated latch bolt and open the door independently of movement of the other handle on the door, locking means associated with said exterior handles for effecting a locking operation exterior of said doors whereby to prevent both said exterior handles and said interior handles from withdrawing said latch bolts, locking means associated with said interior handles for effecting a locking operation interior of said doors whereby to prevent both said exterior handles and said interior handles from withdrawing said latch bolts, locking means associated with said interior handles for effecting a locking operation interior of said doors whereby to prevent both said exterior handles and said interior handles from withdrawing said latch bolts, locking means requiring the restoration of the said locking means that is actuated to effect a locking operation in order to reestablish the operating relation between all said handles and their associated latch bolts to permit said handles to again withdraw said latch bolts, and means associated with all said doors for preventing the operation of both of said locking means if one or more of said doors are not in a position to be latched by said bolts.

15 35 7. A system for locking a plurality of doors comprising, in combination, a latch bolt associated with each door, exterior and interior handles on each door, each handle being adapted to withdraw its associated latch bolt and open the door independently of movement of the other door, mechanism for disabling the operative relation between both handles on each door and their associated latch bolt, an exterior controller, an interior controller, motion transmitting connections between said controllers and said disabling means and operable by said controllers, and means associated with said doors for blocking the operation of said motion transmitting connections if one or more of said doors are not in a position to be latched by said bolts.

20 40 8. A system for locking a plurality of doors comprising, in combination, a latch bolt associated with each door, a handle on each side of each door for withdrawing its associated bolt and opening the door independently of movement of the other handle, an operating connection between each handle and its associated latch bolt, a locking device on each side of said doors for effecting a locking operation from either side of the doors, each of said locking devices disabling said operating connections between the handles of each door and their associated latch bolt, motion transmitting connections between said locking means and said operating connections, and means controlled by the position of said doors for disabling said motion transmitting connections.

25 45 9. A locking mechanism for a door comprising a bolt for engaging an adjacent keeper to keep the door in closed position, a handle on each side of said door for withdrawing said bolt and opening the door independently of movement of the other handle, locking means for disconnecting both handles from said bolt and thereby preventing said bolt from being withdrawn to open

said door, and means for preventing the operation of said locking means if said bolt is not engaged in said keeper.

10. A locking mechanism for a door comprising a bolt for engaging an adjacent keeper to keep the door in closed position, a handle on each side of said door for withdrawing said bolt and opening the door independently of movement of the other handle, locking devices on opposite sides of the door, the operation of either locking device disconnecting both handles from said bolt and thereby preventing said bolt from being withdrawn to open said door, and means for preventing the operation of either locking device if said bolt is not engaged in said keeper.

11. A locking system for a plurality of doors comprising, in combination, a latch bolt associated with each of said doors, bolt actuating means on each door, a post adjacent one edge of each door, means operably disconnecting each bolt actuating means from its associated bolt including a movable part on said adjacent post, means operable from a single station operably associated with said movable part for actuating the same, and means for disabling said movable part if certain of said doors are not in closed position.

12. A locking system for a plurality of doors comprising, in combination, a locking mechanism on each door, locking means for locking one of said locking mechanisms, means for transmitting the locking action of said locking means to the other locking mechanisms including a plurality of movable elements adapted to project from the open edge of each door and intermediate members in the adjacent post operably associated with

said movable elements to transmit motion between said movable elements of all said doors, and means adapted to project between the open edge of each door and the adjacent post preventing operation of said movable elements if certain of said doors are open.

13. A locking mechanism for a door comprising a bolt for engaging an adjacent keeper to keep the door in closed position, a handle on said door for withdrawing said bolt and opening the door, means for rendering said handle ineffective to withdraw said bolt, including a movable part, and a movable member adapted when the door is open to project from the open edge of the door whereby to block the movement of said movable part and render said means inoperative to render said handle ineffective, said movable member being displaceable when the door is moved to closed position.

20 14. A locking mechanism for a door comprising a bolt for engaging an adjacent keeper to keep the door in closed position, a handle on said door for withdrawing said bolt and opening the door, means for rendering said handle ineffective to withdraw said bolt, and a pivotally mounted member disposed within the door adapted to project from the open edge of the door when the door is open, said member having a portion thereof moving into the path of a portion of said 25 means to block the same and prevent the operation of said means when said movable member projects from the open edge of the door, there being means associated with said member adapted to effect camming of said member within 30 the door when the door is closed.

ALEXANDER C. FINDLAY.
